(57) **CLAIM**

I claim the ornamental design for a duck game call device, as shown and described.

DESCRIPTION

FIG. 1 is a front view of the duck game call device.

FIG. 2 is a left view of the claimed design.

FIG. 3 is a right view of the claimed design.

FIG. 4 is a top view of the claimed design; and,

FIG. 5 is a bottom view of the claimed design.

1 Claim, 3 Drawing Sheets

FIG. 1

FIG. 3

FIG. 2

FIG. 4

FIG. 5
